RALPH H. UPSON, OF AKRON, OHIO, ASSIGNOR TO THE GOODYEAR TIRE & RUBBER COMPANY, OF AKRON, OHIO, A CORPORATION OF OHIO.

DIRIGIBLE BALLOON.

1,336,601.

Specification of Letters Patent. Patented Apr. 13, 1920.

Application filed November 9, 1916. Serial No. 130,380.

To all whom it may concern:

Be it known that I, RALPH H. UPSON, a citizen of the United States, residing at Akron, in the county of Summit and State 5 of Ohio, have invented new and useful Improvements in Dirigible Balloons, of which the following is a specification.

My present invention relates broadly to dirigible balloons and is more particularly 10 concerned with that class of dirigibles known as the rigid type, that is, those in which rigid longitudinal bracing is provided for the envelop.

As a principal object, this invention contemplates the provision of a dirigible balloon of this type which is fitted with a number of separate gas compartments, certain 15 of which are provided with independent ballonnets; the whole system of separated 20 compartments being devised with the intention of preventing undue localization of interior pressures at either end of the dirigible, no matter how the latter may be momentarily tipped.

It is a further object of the invention to provide, in connection with the outer wall 25 of the main envelop, an interior sheathing of collapsible sealing pockets, of such nature that this envelop is rendered practically 30 puncture proof without the sacrifice of any of the flexibility or lightness of the ordinary envelop.

It is a still further object of the invention to construct a dirigible with a longitudinal 35 envelop-bracing framework of such nature that all of the housing, cars or compartments intended for the accommodation of the pilots, passengers, engines or fuel supplies may be incorporated into portions of 40 the framework in such a manner that the longitudinal stream line of the balloon is not obstructed. It is a complemental portion of this object to so arrange the separate gas compartments of the main gas envelop with 45 respect to the various housings, cars, and engine and fuel compartments that a symmetrical aspect and proportional distribution of the weights is obtained.

The above and additional objects of a similar nature, which will be hereinafter more 50 specifically treated, are preferably accomplished by such means as are illustrated in the accompanying drawing, described in the following specification, and then more particularly pointed out in the claims which

are appended hereto and form a part of this application.

With reference to the drawing, wherein there has been illustrated a preferred embodiment of the invention as it is reduced 60 to practice, and throughout the several views of which, similar reference numbers designate corresponding parts;

Figure 1 is a longitudinal, sectional view taken through the dirigible provided by this 65 invention;

Fig. 2 is a transverse sectional view taken on the plane of the line 2—2 of Fig. 1;

Fig. 3 is an enlarged sectional detail of the collapsible sealing pockets forming an 70 interior sheathing for the gas envelop; and

Fig. 4 is a rear elevational view of the balloon.

The dirigible comprehended by my present invention has been stated to be of the 75 rigid type. This term is employed as covering the class of balloons having a stiffening framework which defines the gas envelop but does not necessarily inclose the entire envelop, as in the Zeppelin type of dirigible. 80 The gas envelop is of dual formation in that it is longitudinally divided into two compartments by a fabric diaphragm which vertically connects portions of the longitudinal framework. Each of the longitudinal halves 85 of the envelop is subdivided into a plurality of smaller gas compartments by means of transverse fabric diaphragms, which extend completely across their half of the balloon and form an obstruction to the flow of gas 90 in that half. These smaller gas compartments are provided with air ballonnets which operate independently to provide a uniform distention of these smaller compartments. Incorporated into the lower portion 95 of the longitudinal framework of the dirigible are the engine rooms, the passenger cabins and the fuel tanks which are thus positioned to prevent destruction of the stream-line configuration of the balloon and to effect a material reduction in the head resistance of the craft. The entire exterior wall 100 of the balloon fabric is equipped with an interior sheathing of collapsible pockets which are normally in communication. A puncture of any of these pockets is automatically sealed to prevent dissipation of the gaseous 105 contents of the balloon.

The longitudinal framework 10 of the craft is illustrated in Fig. 1 as being sub- 110

stantially elliptical in outline, although partaking of the stream-line configuration fore and aft to which it is desired that the body of the balloon shall conform. Preferably 5 the stiffening structure is composed of plate members 11 which are triangularly grouped in cross-section, as this style of reinforcing element is best adapted to be incorporated into the balloon form which I preferably employ, the latter being substantially "heart-shaped." The lowermost portion of the framework 10, I have enlarged to a quadrangular form in cross-section at spaced intervals along its length in order to provide a 10 fore engine compartment 12, a passenger cabin 13, fuel compartments 14 and an aft engine room 15. The size of the triangle formed by the plates 11 of the framework decreases both fore and aft from the amidship portions of the dirigible, as a matter of 15 design.

The flexible envelop portions 16 inclosing the fluid of inflation arch away on each side from the upper portion of the framework 20 and curve downwardly to a securement along the framework's lower half. Thus, the balloon envelop as an entirety is heart-shaped in cross section as illustrated in Figs. 2 and 4. The opposite longitudinal halves of this 25 elongated "heart" are separated by the partition 17 which vertically connects the upper and lower portions of the framework 10.

All of the exposed surface of the exterior fabric 16 is equipped with an interior sheathing of collapsible pockets 18 arranged in longitudinally extending series from the nose to the tail of the craft, with the pockets of adjacent series in the abutting relation illustrated which also arranges the pockets in 30 conterminous transverse series. The pockets 18 of each transverse series are in communication through the medium of small valve holes 19 provided in their dividing walls 20. The wall 20 between each pair of adjacent 35 pockets of a transverse series is bifurcated in the manner denoted by the numeral 21 to provide the back walls 22 of the adjoining pockets. Each of these back walls is formed with a padded protuberance 23 which bears 40 such relation to the valve hole 19 that a collapse of the pocket which forces the back wall against the face wall 16 of each pocket, due to the pressure of the gas in the main compartment, will move the pad over the 45 valve hole and shut off all communication between the collapsed pocket and the remaining pockets of its transverse series.

Normally, these pockets 18 are filled simultaneously with gas to their proper limit of 50 expansion and are kept by suitable gas pumps at a pressure in excess of that existing in the main compartments. Should the dirigible be subject to rifle fire, it will be apparent that the projectile to damage the interior of the balloon must pass through the

exterior fabric 16 and also the back wall 22 in the pocket, covering the surface portion struck by the projectile. Any pocket which is thus punctured exhausts its gas into the atmosphere and is then collapsed by the outward pressure of the main gas compartments 70 so that its back wall 22 is forced into underlying relation against the inner face of the exterior covering 16. This movement, as is apparent from an inspection of the collapsed 75 pocket shown in Fig. 3 not only closes off the punctured pocket 18 from the others of its series but also prevents the bullet holes from registering and so providing a path of escape 80 for the contents of the main gas compartments, except, of course, in the rare and single instance in which the projectile is directly perpendicular to the central axis of the pocket. These pockets in their normal condition also serve to stiffen the envelop 85 against lateral distortion.

The interior of each half of the balloon is subdivided by a plurality of paired partitions 24 which may be symmetrically arranged between adjacent engine, cabin or 90 fuel compartments provided in the lower framework portion. These separate gas compartments which have been lettered G' in distinction to the main gas compartments lettered G extend between the central partitions 17 and the exterior fabric covering 16 in such a manner as to form a complete obstruction of any flow of the gases between the compartments G. Each of these obstructing compartments is provided with 100 a balloonet diaphragm 25 which defines an air compartment labeled B. Air inlet openings 26 are provided in communication with the exterior atmosphere and the balloonets B to accomplish the usual automatic regulation of the gas pressures within the compartments G', which similarly in their turn are able to expand or contract to raise or lower the pressures within the main gas compartments G. 105

The main incentive for the adoption and use of the smaller obstructing gas compartments G' is that employment of these compartments prevents any flow longitudinally of the balloon which takes place in the ordinary type of dirigible when the craft is tipped at either end. This is recognized as dangerous for the reason that it results in a localization of gas pressures at some particular point of the retaining fabric, which 115 will then be subjected to unusual strain. Any tendency toward the localization of pressures, when the dirigible of my invention is tipped at either end, is split up and distributed by the obstructing gas compartments in such a manner as to avoid the creation of undue pressures. This system has the further advantage of permitting the use of a less cumbersome means for maintaining the balloon envelop to its proper limits 120 125 130

of distention, since the small ballonet dia-
phragms 25 and the secondarily expansible
diaphragms 24 coöperate to this end.

Those portions of the envelop 16 which
5 normally extend to the bottom of the lower
framework 10, opposite the various hous-
ings for the cabin, engine and fuel com-
partments are so constructed as to provide what
10 may be termed laterally extending tunnels
in the manner illustrated in Fig. 2. The
propellers 27 of the engine are mounted as
the extremities of outrigger frameworks 28
which project through the lateral tunnels
mentioned. The passenger cabin 13 is also
15 provided with increased means of observa-
tion by the construction of the envelop 16 to
provide these tunnels, and may, in addition
be built with a transparent flooring.

Any suitable form of empennage may be
20 employed upon the tail of the dirigible, as
for instance, the form here illustrated of
fixed planes 29 which are grouped in pairs,
as shown in Fig. 4, and support the tri-form
rudders 30 and elevators 31. Bumpers 32
25 of any suitable material may be employed
to support the engine compartments, the fuel
compartments at a common level when the
dirigible is at rest upon the ground, in
order to lessen the strain upon the lower
30 portion of the framework.

While in the foregoing I have thus de-
scribed and illustrated the instrumentalities
whereby I propose the accomplishment of
the objects previously stated to be essential
35 to this invention, I desire to emphasize the
fact that I may resort to such alterations in
the matters of proportion and degree as
shall appear to be desirable in later adap-
tations of my balloon design, as the latter is
40 defined in the appended claims.

What I claim is:

1. In a balloon, a framework including an upper and a lower longitudinally extending member defining an elevational stream line for the balloon; and gas containing envelopes connecting said upper and lower members of the framework, said envelopes having a common longitudinally extending partition wall.
- 45 2. In a balloon, a longitudinal framework defining an elevational stream line for the balloon; and gas containing envelopes connecting opposite portions of the framework

to provide a balloon of substantially "heart-
shaped" cross-section.

3. In a balloon, a longitudinally disposed
framework defining an elevational stream
line for the balloon; a diaphragm vertically
connecting opposite portions of the frame-
work; and envelop portions oppositely con-
necting the framework portions to provide
a balloon formed of longitudinal halves sep-
arated by said diaphragm.

4. In a balloon, a longitudinally disposed
framework defining an elevational stream 65
line for the balloon; a diaphragm vertically
connecting opposite portions of the frame-
work; and envelop portions oppositely con-
necting the framework portions to provide a
balloon having a "heart-shaped" cross-sec- 70
tion of longitudinally distinct halves.

5. In a balloon, a framework comprising
upper and lower longitudinally extending
members defining an elevational stream line,
housings incorporated at intervals into one 75
portion of said members; a gas envelop sup-
ported upon the framework; and separate
gas compartments arranged within said en-
velop at intervals corresponding to those be-
tween said housings.

6. In a balloon, a gas envelop and pockets
forming a continuous sheathing for the in-
terior of the exposed portions of the en-
velop, said pockets being arranged in series
communicable transversely of the balloon; 85
means to prevent communication between a
punctured pocket and the adjacent pockets
of its series and means to collapse the punc-
tured pocket to seal the holes of the punc-
ture.

7. In a balloon, a gas envelop, pockets
forming a continuous sheathing for the in-
terior of the exposed portions of the en-
velop, ports normally affording communica-
tion between the pockets, and means adapt-
ed to automatically close the ports, between 95
any given pocket and the immediately adja-
cent pockets, immediately upon the punc-
turing of a wall of such given pocket.

In testimony whereof I have signed my 100
name in the presence of two subscribing wit-
nesses.

RALPH H. UPSON.
